UNITED STATES PATENT OFFICE

2,397,685

DEVICE FOR DISTRIBUTION OF ACCOUNTS

Frederick A. Niemann, Chicago, Ill., assignor to
Felt & Tarrant Manufacturing Company, Chi-
cago, Ill., a corporation of Illinois

Application October 13, 1943, Serial No. 506,029

2 Claims. (Cl. 129—1)

This invention relates to a record sheet holder for facilitating the distribution of accounts and for facilitating computation from a multiplicity of separate similar record sheets or strips. A plurality of the record sheets or strips provided with columns of numerical data are arranged and maintained in such a record sheet holder in parallel and overlapping relationship with only a desired column or columns of each sheet or strip exposed whereby to facilitate the lateral addition or extension of the corresponding items in the various columns.

The invention has more particular reference to a novel and improved record sheet holder construction which facilitates and expedites the removal of the record sheets or strips from the record sheet holder without disturbing or changing their order whereby the removed record strips may be quickly and readily gathered or collected for filing or other subsequent use.

An important object of the invention is the provision in such a record sheet holder of means for facilitating and expediting removal of the record sheets or strips from the sheet retaining means of the record sheet holder.

Another important object of the invention is the provision of a record sheet ejector which is adapted in operation to remove the overlapping record sheets or strips from such a record sheet holder with a minimum of mutilation of the record strips and without disturbing or changing their order of arrangement.

Other objects and advantages of this invention will be understood from the following description which considered with the accompanying drawings discloses a preferred embodiment of the invention.

Referring to the accompanying drawings:

Fig. 1 is a perspective view of a record sheet holder with a plurality of record sheets or strips arranged and held therein, embodying some of the features of the invention;

Fig. 2 is a fragmentary cross-section of the improved record sheet holder shown in Fig. 1 and is taken longitudinally of the sheet clamping means and the novel means for facilitating the removal of the record sheets or strips;

Fig. 3 is a fragmentary cross-section of the improved record sheet holder and is taken transversely of the sheet clamping means substantially along the lines 3—3 of Fig. 1.

Fig. 4 is a plan view of the record sheet clamping means with portions broken away or otherwise removed to show the record sheet ejector in its relationship to the sheet retaining means

preparatory to the removal of the record sheets or strips;

Fig. 5 is an elevational view of the sheet clamping means with portions broken away or otherwise removed to show the position of the sheet ejector relative to the sheet clamping means after the sheet ejector has ejected the record sheets or strips;

Fig. 6 is a cross-section of the novel record sheet clamping and ejecting means taken substantially along the lines 6—6 of Fig. 4, and

Fig. 7 is a cross-section of the novel record sheet clamping and ejecting means taken substantially along the lines 7—7 of Fig. 5.

Illustrative of the invention, the drawings show a record sheet holder like that disclosed in United States Letters Patent of Frederick A. Niemann, No. 2,033,147 issued March 10, 1936, and novel means for facilitating the removal of the record sheets or strips therefrom. Since such a record sheet holder as disclosed herein for convenience in illustrating the invention is fully disclosed in the above mentioned patent, only so much of such a holder will be described herein as may be necessary or desirable for a complete understanding of the present invention.

Briefly, as shown in Figs. 1 to 3 the illustrated record sheet holder comprises a suitable backing support 11 and sheet clamping means generally indicated by the reference character 12, adapted for attachment to the support 11. The sheet clamping means is preferably of the type adapted to receive and hold a plurality of record sheets or strips 13 in parallel overlapping relationship on support 11. If desired a T square or other suitable line guide 14 is arranged across the backing support to facilitate lateral reading across the assembled sheets or strips.

As illustrated the sheet clamping means 12 comprises a pin or peg carrying plate or other suitable sheet retaining means 15. The clamping means 12 is attachable to and detachable from a side margin of the backing support 11 by suitable attaching means such as headed pins 16 spaced apart along the side margin of and carried by the backing support 11 and a pair of correspondingly spaced key-hole slots or notches 17 extending in from opposite side edges adjacent each end of the peg carrying plate 15. That plate 15 is provided with a plurality of pins or pegs 18 anchored at regularly spaced intervals along the plate by rivets 19 or other suitable securing means and projecting outwardly from a face of the plate 15 for receiving the record sheets or strips 13. A hollow tubular confining or

clamping member 21 of resilient flexible metal and substantially horse-shoe shaped in cross section, i. e. with a longitudinal slot 22, is adapted to be pressed over the pegs 18 for cooperating with the plate 15 releasably to clamp and hold the positioned sheets or strips 13 against inadvertent displacement during the use of the record sheet clamping means.

From the above mentioned Patent No. 2,033,147, it will be understood by those skilled in the art that the record sheets or strips 13 are duplicates of each other and are printed alike on both sides as disclosed more fully in United States Letters Patent of Frederick A. Niemann and Kurt F. Ziehm, No. 1,884,814, issued October 25, 1932. Each side of each such strip is provided with marginal columns 23 and 24 and a center or intermediate column 25 and each such strip is provided near its top edge with perforations 26 spaced apart a distance equal to the space between succeeding pegs 18.

A plurality of the strips 13 in one use of the record sheet holder is impaled on the pegs 18 in such a manner that the strips are in parallel and overlapping relationship with corresponding marginal columns of the strips exposed and with the transverse lines of each exposed column forming continuations or extensions of each other. When the strips are suitably arranged in position on the peg carrying plate 15, the slot 22 of the strip confining or clamping member 21 is brought into registration with the outer ends of the pegs 18 and the clamping member is pressed toward the plate 15. Due to the resiliency of the clamping member, it is thus movable into frictional locking engagement with the pegs and will hold the record sheets or strips on the pegs 18 against inadvertent displacement during calculation, during reversing of the clamping means with its contained sheets or strips, and during other uses of the assembled sheets and sheet clamping means.

In removing the multiplicity of strips 13 from such a record sheet holder, the strip confining or clamping member 21 is first disengaged from the pegs 18 by holding the plate 15 and pulling the strip clamping member in a direction away from the plate 15. After such removal of the strip clamping member, it is customary to strip the record strips from the pegs 18 by grasping one or more of them and, while holding the plate 15, pulling upwardly until the strip or strips clear the ends of the impaling pegs 18. In so withdrawing the strips 13 from the pegs 18, many of the strips are frequently torn or otherwise mutilated, and they are disarranged as to order, thus introducing difficulties in filing or other subsequent use of the strips.

It is an object of this invention as already pointed out hereinabove to facilitate the removal of the record sheets or strips from the record sheet holder. To that end, according to the present invention, the record strips 13 are substantially simultaneously removed or separated from the pegs 18 by moving the pegs 18 out of the perforations 26 along paths that are substantially vertical with respect to the record strips, without disturbing the order of the strips. For so ejecting the strips 13, novel means is arranged in engagement with the lower face of the assembled record strips about the pegs 18.

Such means in its present preferred form comprises a resilient ejector strip or plate 27 of metal having a plurality of equally spaced apertures

28 therein spaced apart a distance equal to the spacing of the pegs 18 and of such size as to receive the respective pegs therein. The ejector strip 27 is preferably of a length slightly greater than the intended width of the assembled record strips 13 and is somewhat wider than the peg carrying plate 15. In use the ejector strip 27 is arranged adjacent the peg carrying plate 15 with the pegs 18 extending through the apertures 28 before the record strips 13 and the clamping member 21 are assembled on the pegs 18.

As shown best in Figs. 1 and 3 when so assembled the ends of the ejector strip 27 are accessible at opposite margins of the assembled record strips 13 and the longitudinal margins of the strip 27 extend beyond the corresponding margins of the peg carrying plate 15. By holding either the peg carrying plate 15 or the ejector strip 27 and applying a sufficient force to the other of those members in a direction away from the held member, the assembled record strips 13 are separated or removed from the pegs 18. Thus the ejector strip 27 constitutes convenient means for simultaneously ejecting all of the record strips from the sheet retaining means.

Preferably the improved record sheet holder has associated therewith novel means for operating the ejector strip 27 to remove the record strips from the record sheet holder. Such means is shown in Figs. 4 to 7 and as therein illustrated comprises a supporting holder 29 for the ejector strip 27 and a member 30 engageable with the outer ends of the pegs 18 for forcing the pegs out of the record strip perforations 26 while the ejector strip is supported on the holder 29. The supporting holder 29 is stamped or otherwise formed as an elongated channel or U-shaped member of a length substantially equal to the length of the ejector strip 27, and with a base or bottom wall 31 and upstanding side walls 32 integral therewith. The side walls 32 are spaced apart a distance slightly greater than the width of the peg carrying plate 15 and less than the width of the ejector strip 27 and are of a height substantially equal to or greater than the length of the pegs 18.

The ejector strip supporting holder 29 is thus adapted to receive the peg carrying plate 15 between the spaced side walls 32 and to engage the lower face of the ejector strip 27 outwardly of the opposite longitudinal margins of the peg carrying plate and to hold the ejector strip in that position while the plate 15 is moved downwardly between the side walls 32 of the holder 29 sufficiently to remove the pegs 18 out of the perforations of any and all record strips 13 which may have been impaled thereon. For so moving the plate 15, the member 30 is stamped or otherwise formed of any suitable shape such as a channel to provide a peg engaging portion 33 of such length and width as to be engageable with the outer ends of all of the pegs 18 at the same time, and a portion or portions 34 to facilitate handling and manipulating the member 30 in applying force to the pegs for removing them from the perforations in the record strips.

In the use of the novel ejector operating means, after the clamping member 21 is removed from the pegs 18, the sheet retaining means or peg carrying plate 15 with the ejector strip 27 impaled on the pegs 18, between the peg carrying plate and the impaled record strips is arranged on the channel shaped member 29 as shown in Figs. 4 and 6. In that position the ejector strip 27

rests, at opposite sides of the peg carrying plate 15, on the upper edges of the side walls 32. Thus the side walls 32 support the assembled record strips, ejector strip, and peg carrying plate with the peg carrying plate 15 inwardly of the spaced channel walls 32 below the ejector strip 27 and with the record strips 13 on the ejector strip.

With the sheet retaining means thus arranged on the channel shaped member 29, the peg engaging portion 33 of the member 30 is brought into engagement with the upper free ends of the pegs 18 and pressed downwardly with sufficient force to move the peg carrying plate 15 downwardly into the channel shaped member 29 whereby to remove or withdraw the pegs 18 downwardly through the perforations 26 of the record strips 13 and the apertures 28 in the ejector strip 27. Figs. 5 and 7 show the retaining means after it has thus been released.

In so moving the retaining means, the pegs 18 move in a substantially vertical direction relative to the plane of the perforations 26 of the record strip 13. Hence mutilation of the record sheets is minimized and a minimum of friction between the perforated record strips 13 and the several pegs 18 is encountered during the ejecting operation. Particular attention is directed to the fact that when the sheet retaining means is so operated the arrangement of the record strips 13 is not disturbed and they remain as shown in Figs. 5 and 7 in their original order between the member 30 and the ejector strip 27 and may be readily gathered or collected for filing or other use simply by removing the member 30 from the upper ends of the record strips.

It is thought that the invention and many of its attendant advantages will be understood from the foregoing description and it will be apparent that various changes may be made in the form,

construction and arrangement of the parts without departing from the spirit and scope of the invention or sacrificing all of its material advantages, the form of the invention hereinabove described being merely a preferred embodiment thereof.

I claim:

1. In a record sheet holder including sheet impaling means having a multiplicity of record sheets impaled thereon, a sheet ejector impaled on said impaling means under said record sheets, means engaging said sheet ejector at the side thereof opposite said record sheets for supporting the assembled sheet impaling means, sheet ejector, and record sheets at a height greater than the length of said sheet impaling means, and means engageable with said sheet impaling means while it is so supported and adapted to move it downwardly relative to said sheet ejector from impaling relationship with said record sheets for simultaneously ejecting all of the record sheets from said impaling means.

2. In a record sheet holder including a peg carrying plate having a plurality of spaced upstanding pegs for impaling thereon a multiplicity of paper sheets, a sheet ejector impaled on said pegs between said plate and paper sheets and having marginal portions extending outwardly beyond opposite edges of said plate, means engageable with the sheet ejector marginal portions outwardly of the opposite edges of said plate for supporting the assembled plate, sheet ejector and record sheets in sheet ejecting position, and means engageable with said pegs for moving them and said plate relative to said sheet ejector while said sheet ejector is held by the last said means to remove all of the paper sheets from said pegs.

FREDERICK A. NIEMANN.
